COOLING SYSTEM

William H. Nebgen, Woodside, N.Y., assignor to Chemical Construction Corporation, New York, N.Y., a corporation of Delaware

Filed Apr. 8, 1963, Ser. No. 271,319
11 Claims. (Cl. 62—98)

This invention relates to an improved cooling system for the cooling of fluids by heat exchange with a volatile refrigerant. A new sequence is provided which permits the effective cooling of a fluid using both the sensible heat and the latent heat of vaporization of the refrigerant. The system of the present invention is most suitably applicable in combination with multi-stage gas compression to provide interstage cooling. In this combination, a substantial reduction in total gas compression horsepower requirement is achieved.

Numerous variations on the basic refrigeration cycle have been proposed in the prior art. Typical of these are the systems disclosed in U.S. Patents 2,156,096; 2,225,491 and 2,389,106. In these and other similar types of refrigeration systems, the basic means of achieving a cooling effect is through vaporization of a volatile refrigerant while in heat exchange with the fluid being cooled. The resulting refrigerant vapor is compressed, cooled and condensed, and recycled as liquid refrigerant. In some cases, sub-cooling of the liquid refrigerant may take place, so that part of the heat load is carried as sensible heat, in warming up the liquid refrigerant to vaporization temperature. However, such heat transfer via heating of the liquid refrigerant prior to vaporization forms in most cases only a very minor proportion of the total cooling effect.

In the present invention, an apparatus arrangement of a refrigeration system and a refrigeration method are provided, which accomplish substantial sub-cooling of the liquid refrigerant and thus permit removal of a substantial portion of the heat load as sensible heat of liquid refrigerant. The sub-cooled liquid refrigerant is passed in heat exchange with the fluid being cooled, and the liquid refrigerant is thus warmed and partially vaporized. The mixed vapor-liquid stream is withdrawn from the heat exchange unit, and is separated into vapor and liquid components. The vapor component is combined with a recycle vapor stream derived from flash cooling, and the combined vapor stream is cooled and condensed to liquid refrigerant. This liquid stream is combined with the liquid component derived from the heat exchange unit. The combined liquid stream is passed through an expansion valve to a lower pressure level, and a flash cooling effect is obtained which cools the liquid refrigerant. The expansion also produces a vapor stream, which is compressed and recycled for combination with the vapor component derived from the heat exchange unit as discussed supra. The cooled liquid refrigerant is pumped up to normal pressure, thus becoming sub-cooled at the pump discharge pressure, and is recycled to the heat exchange unit.

The cooling system of the present invention has outstanding advantages. Thus, it has been proposed that a fluid may be cooled in two stages, using cooling water for partial cooling in a first heat exchanger and volatile liquid refrigerant for final cooling in a second heat exchanger. In the system of the present invention, the entire cooling load may be carried by the single heat exchanger unit, with a net saving in total heat exchanger surface required. In addition, when the system of the present invention is applied to interstage cooling of a gas stream between stages of compression, it has been found that a substantial reduction in total compression power

2

requirement is obtained. In this case, the compression power required at each stage of compression is substantially reduced due to the fact that the inlet temperature of the gas stream to each stage of compression is lowered by refrigerant cooling, while the total added power requirement for recycle of vapor and liquid refrigerant components from the flash cooling stage is quite small in comparison to the reduction in gas compression power requirement.

10 It is an object of the present invention to provide an improved cooling system using a volatile liquid refrigerant.

Another object is to provide a cooling system in which sensible heat of the liquid refrigerant is employed to 15 achieve a cooling effect.

A further object is to provide a cooling system in which more effective utilization of heat exchange surface is achieved.

An additional object is to provide a cooling system in 20 which sub-cooling of liquid refrigerant is accomplished by separate decompression and flash cooling of the liquid refrigerant.

Still another object is to provide a cooling system in 25 combination with a plurality of stages of gas compression, such that interstage cooling is accomplished with reduced net compression power requirements.

These and other objects and advantages of the present invention will become evident from the description which follows. Referring to the figure, a generalized flow diagram of the apparatus arrangement and system of the 30 present invention is presented, as applied to the cooling of a fluid. In the following description, the method and flow diagram will be described in relation to use of ammonia as the volatile liquid refrigerant. It will be appreciated that other volatile liquid refrigerants, such as 35 freon, propane and butane may be employed in the present invention instead of ammonia.

The sub-cooled liquid ammonia stream 1, typically at 40 a pressure in the range of 250 p.s.i.g. to 300 p.s.i.g. and temperature of 0° F. to 32° F., is passed into heat exchange unit 2. Stream 1 may be at a temperature of 32° F. or slightly higher in cases where the fluid being cooled contains water vapor, so as to avoid deposition of solid ice in the heat exchange unit. Depending on the 45 properties of the fluid being cooled, other temperature levels for stream 1 may be provided. It will thus be evident that the ranges of pressure and temperature recited supra for stream 1 are merely typical or preferable, and are not to be construed as restrictive on the scope of the 50 present invention. Similar considerations apply with respect to operating ranges of temperature and pressure recited infra.

Stream 1 passes through the coil 3 of heat exchanger 55 unit 2, and is heated to a temperature typically in the range of 110° F. to 125° F. Vaporization of a portion of the liquid ammonia also occurs. The fluid to be cooled is passed via 4 into unit 2, and is cooled by heat exchange with the ammonia, leaving unit 2 via 5 at a desired lower temperature. In a preferred embodiment, stream 4 is 60 derived from compression stage 25 of a gas compressor, and stream 5 is passed to the next higher compression stage 26 of the gas compressor.

The warmed and partially vaporized ammonia stream 65 leaves coil 3 via 6, and passes into gas-liquid separator unit 7, which may be of cyclonic configuration. Other suitable designs for unit 7 including interior baffles may be provided, to accomplish the division of stream 6 into vapor and liquid components. The vapor component is withdrawn from unit 7 via 8, and stream 8 is combined with recycle vapor stream 9, which is derived from the 70 flash cooling stage of the system in a manner to be de-

scribed infra. The combined vapor stream 10 now passes into vapor condenser 11, in which the vapor is condensed to liquid ammonia. Cooling water or other cooling medium is passed via 12 to the cooling coil 13 of unit 11, and warmed cooling water is withdrawn via 14.

The resulting condensed liquid ammonia is withdrawn via 15 from unit 11, typically at a temperature in the range of 70° F. to 100° F. Stream 15 is now combined with the residual liquid ammonia stream 16 withdrawn from the separator 7, to form combined liquid ammonia stream 17. The liquid ammonia stream is now cooled by expansion and decompression to a reduced pressure level. Thus, stream 17 is passed through expansion valve 18, and is discharged via 19, passing directly into flash cooler 20 in which a reduced pressure level typically in the range of 30 p.s.i.g. to 62 p.s.i.g. is maintained. Flash cooler 20 is a suitable vessel in which substantial equilibrium is achieved between the flashing ammonia vapor and residual liquid, such that a reduced equilibrium temperature in the range of 0° F. to 32° F. is attained due to the spontaneous evolution of ammonia vapor at the reduced pressure.

The evolved ammonia vapor is withdrawn from unit 20 via 21, and is compressed by compressor 22 to a pressure level suitable for recycle and in the range of about 250 p.s.i.g. to 300 p.s.i.g. The compressed vapor is discharged 25 from unit 22 via 9, and is recycled in a manner described supra.

The cooled liquid portion is withdrawn from unit 20 via 23 at a temperature in the range of 0° F. to 32° F., and is pressurized by pump 24 to the required pressure 30 level for recycle, in the range of 250 p.s.i.g. to 300 p.s.i.g. The pressurized and sub-cooled liquid ammonia stream is then recycled via 1 for further service as a coolant in the heat exchange unit 2 as described supra.

Numerous variations within the scope of the present 35 invention will occur to those skilled in the art. Thus, for example, the various processing units have been illustrated only in a schematic manner. In actual practice, apparatus units of differing design may be employed to carry out the functions of the respective apparatus elements illustrated in the flow diagram.

Example

An example of an industrial application of the present invention with its concomitant advantages will now be described. The apparatus system and cooling method of the present invention was applied to the interstage cooling of ammonia synthesis gas between three stages of compression from an inlet pressure of 204 p.s.i.g. to a final discharge pressure of 5100 p.s.i.g. Compression discharge temperature of the gas was 230° F. at each stage, and the gas stream was cooled to 40° F. in accordance with the present invention, prior to further compression. The ammonia coolant was admitted to the heat exchange unit at 21° F., and a mixed vapor-liquid stream of ammonia was recovered at 110° F.

It was determined that the total compression load was reduced by 1100 horsepower for a plant handling 3462 mols/hour of dry synthesis gas, due to reduction in the interstage volume of the synthesis gas which was achieved by the cooling system of the present invention. The power required for compression of recycle ammonia vapor and pumping of subcooled liquid ammonia was only 30% of the power saving achieved due to reduction in the loading of the main gas compressor. In addition, the total heat exchange surface required was only 90% of that required in previous systems, where cooling was accomplished in a conventional manner using cooling water and vaporizing ammonia in two stages of cooling. Finally, the net interstage gas pressure drop was reduced by 25 p.s.i. due to the fact that the process synthesis gas was passed through one heat exchanger rather than the two units required in prior practice.

What I claim is:

1. In a cooling system, the combination of a cooler

for heat exchange between a fluid being cooled and a sub-cooled volatile liquid refrigerant at elevated pressure, wherein said liquid refrigerant is heated and partly vaporized at said elevated pressure, a separator for division of heated refrigerant into vapor and residual liquid phases, means to pass said heated refrigerant from said cooler to said separator, a condenser for conversion of the refrigerant vapor phase combined with a vaporized refrigerant portion to liquid without compression, means to pass said refrigerant vapor phase and said vaporized refrigerant portion to said condenser, means to combine liquefied refrigerant from said condenser with said residual liquid phase derived from said separator, an expansion valve for cooling of said combined liquid refrigerant by expansion to reduced pressure, whereby a portion of said liquid refrigerant is vaporized, means to pass said combined liquid refrigerant through said expansion valve, a flash cooler for cooling of liquid refrigerant by said expansion to reduced pressure and separation of cooled vapor and liquid phases, means to pass refrigerant vapor-liquid mixture to said flash cooler from said expansion valve, a vapor compressor for compression of the cooled vapor portion from said flash cooler, whereby said vaporized refrigerant portion is produced, a pump for pressurizing and return of sub-cooled liquid refrigerant to said cooler, and means to pass the cooled liquid portion from said flash cooler to said pump.

2. Cooling system of claim 1, in which said condenser for conversion of the refrigerant vapor phase combined with a vaporized refrigerant portion to liquid without compression is a water cooled condenser.

3. Method of cooling a fluid with a volatile liquid refrigerant which comprises cooling a fluid by heat exchange with sub-cooled liquid refrigerant at elevated pressure, thereby heating said refrigerant to a higher temperature and forming separate vapor and liquid phases at said elevated pressure, combining the vapor phase with a stream of compressed vaporized refrigerant at said elevated pressure cooling the combined vapor stream at said elevated pressure to form condensed liquid refrigerant without compression, combining said condensed liquid refrigerant with said liquid phase, expanding the combined liquid stream to reduced pressure whereby a portion of said liquid stream is vaporized and a cooling effect is obtained, compressing the vaporized portion of refrigerant, recycling the compressed vaporized portion of refrigerant to said step of combining with the vapor phase as said stream of compressed vaporized refrigerant, pressurizing the cooled liquid stream whereby said liquid stream is sub-cooled, and recycling said sub-cooled liquid stream to said fluid cooling step as said sub-cooled liquid refrigerant.

4. Method of claim 3, in which said volatile liquid refrigerant is ammonia.

5. Method of claim 3, in which said volatile liquid refrigerant is Freon.

6. Method of claim 3, in which said volatile liquid refrigerant is propane.

7. Method of claim 3, in which said volatile liquid refrigerant is butane.

8. Method of claim 3, in which said combined vapor stream is cooled to form condensed liquid refrigerant by heat exchange with liquid water.

9. Method of cooling a fluid with ammonia which comprises cooling a fluid by heat exchange with sub-cooled liquid ammonia, said liquid ammonia being at an elevated pressure in the range of 250 p.s.i.g. to 300 p.s.i.g. and temperature in the range of 0° F. to 32° F., whereby said liquid ammonia is heated to a temperature in the range of 110° F. to 125° F. and a separate ammonia vapor phase is formed at said elevated pressure, combining the ammonia vapor phase with a compressed recycle stream of ammonia vapor, cooling the combined vapor stream at said elevated pressure to form condensed liquid ammonia without compression at a temperature in the range of 70° F. to 100° F., combining said condensed

liquid ammonia at said elevated pressure with the unvaporized liquid ammonia component remaining after said fluid cooling step, expanding the combined liquid ammonia stream from said elevated pressure to a reduced pressure in the range of 30 p.s.i.g. to 62 p.s.i.g. whereby a portion of said liquid ammonia stream is vaporized and the ammonia temperature is reduced to the range of 0° F. to 32° F., compressing the vaporized portion of ammonia to a pressure in the range of 250 p.s.i.g. to 300 p.s.i.g. recycling the compressed ammonia vapor stream to said cooling step as said recycle stream of ammonia vapor, pressurizing the cooled liquid ammonia to an elevated pressure in the range of 250 p.s.i.g. to 300 p.s.i.g., whereby said liquid ammonia is sub-cooled and recycling the sub-cooled liquid ammonia to said fluid cooling step.

10. Method of interstage cooling in gas compression in a plurality of stages which comprises compressing a gas stream to an intermediate pressure level, cooling the partially compressed gas stream by heat exchange with a sub-cooled volatile liquid refrigerant which is at an elevated pressure, further compressing the cooled gas stream in the next stage of compression, heating said volatile liquid refrigerant to a higher temperature level at said elevated pressure by said heat exchange with formation of separate vapor and liquid phases, combining the vapor phase at said elevated pressure with a stream of compressed vaporized refrigerant, cooling the combined vapor stream to form condensed liquid refrigerant without com-

5
10
15

pression, combining said condensed liquid refrigerant with said liquid phase, expanding the combined liquid stream to reduced pressure whereby a portion of said liquid stream is vaporized and a cooling effect is obtained, compressing the vaporized portion of refrigerant, recycling the compressed vaporized portion of refrigerant to said step of combining with the vapor phase as said stream of compressed vaporized refrigerant, pressurizing the cooled liquid stream whereby said liquid stream is sub-cooled, and recycling said sub-cooled liquid stream to said heat exchange step as said sub-cooled volatile liquid refrigerant.

11. Method of claim 10, in which said gas stream is ammonia synthesis gas and said volatile liquid refrigerant is ammonia.
